A. DOLMATCH
EXPANDABLE VAGINAL SYRINGE

Filed Aug. 16. 1926

Inventor:
Aaron Dolmatch,
By his Attorney, A. Ade Comeville

Patented Apr. 17, 1928.

UNITED STATES PATENT OFFICE.

AARON DOLMATCH, OF BAYONNE, NEW JERSEY.

EXPANDIBLE VAGINAL SYRINGE.

Application filed August 16, 1926. Serial No. 129,422.

This invention relates to an expandible vaginal syringe.

The object of the invention is the production of a syringe, adapted to simultaneously expand the folded mucous membrane of the vaginal vault and inject an irrigating fluid therein. The second object of the invention is the production of a syringe with detachable expandible fingers to easily clean them and the other parts of the syringe.

In the accompanying drawings Fig. 1 represents a side elevation of an exemplification of the improved expandible vaginal syringe; Fig. 2 shows a section of Fig. 1 on the line 2, 2; Fig. 3 indicates a section of Fig. 2 on the line 3, 3; Fig. 4 represents a top plan view of Fig. 2 with portions broken away; Fig. 5 shows an elevation of a fragmentary portion of the syringe with a modification; Fig. 6 indicates a section of Fig. 5 on the line 6, 6; Fig. 7 represents a fragmentary longitudinal section of the syringe with a further modification and Fig. 8 indicates an elevation on a reduced scale of a detail.

Referring to Figs. 1 to 4 inclusive and Fig. 8 the syringe is indicated with the compressible bulb shown in its entirety by the numeral 20. The said bulb comprises the usual curved side wall 21, the bottom wall 22 and the head 23. Supplemental inner side walls 28 extend from the wall 21 and the head 23. The walls 28 have each formed therewith the lower member 29 at right angles thereto. The walls 21 and 28 with their members 29 form the pockets 30, which extend through the heads 23. Openings 31 are formed in the walls 21 and extend to the pockets 30.

The nozzle of the syringe is indicated with its wall 34, the crown 35 at one end and the usual bulb 36 having the opening 37 at its other end. Opposite sides of the wall 34 are increased in thickness to form the thickened wall portions 38 and 39. Seating grooves 40 are formed between the portions 38 and 39. The upper ends of the grooves 40 are connected by the curved cross groove 41, and beyond the cross groove 41 are formed the pyramidal portions 42. The thickened portions and pyramidal portion are disposed to obtain smooth surfaces for the nozzle. Openings 43 and 44 are formed in the nozzle.

A pair of expandible arms are each indicated with the pair of fingers 48, joined at their outer ends by the curved connecting

member 49. A spoon shaped shank 50 extends from the lower ends of the fingers 48. The shanks 50 are located in the pockets 30. The fingers 48 are normally seated in the grooves 40 and the connecting members 49 are normally seated in the cross grooves 41. The shanks 50 are located in the pockets 30, by entering the fingers 48 through the openings 31 and positioning the lower ends of the shanks 50 to bear against the lower members 29.

To use the syringe it is first filled with the irrigating fluid, which may be accomplished by immersing the upper end of the nozzle 70 having the wall 34 therein, and then compressing and releasing the bulb 20, by virtue of which the fluid is drawn into said bulb through the openings 43 and 44. In this operation the said bulb 20 is preferably 75 compressed at its wall between the shanks 50. The nozzle of the syringe is now inserted in the vaginal cavity and the bulb 20 is compressed by bearing thereon over the shanks 50, by means of which the fingers 48 80 are swung outwardly and the folds of the membrane of the vaginal vault are expanded, and at the same time the fluid in the bulb 20 is discharged through the openings 43 and 44 into the vaginal cavity. The 85 upper ends 50^a of the shanks 50 are located in the portions of the openings 30, that extend through the head 23 and constitute fulcrums for the fingers 48 and said shanks.

In the modification indicated in Figs. 5 90 and 6, the bulb is again indicated at 20 with its head 23. The nozzle is again shown with its wall 34. The expandible fingers are again shown with the pair of fingers 48, which extend from the shank 50^b having in 95 this instance parallel edge walls 50^c in line with the sides of the fingers 48. In this modification no openings like 31 are made in wall 21 of the bulb 20, and the shanks 50^b are entered into the pockets 30 through their 100 open ends in the head 23.

In the form of the invention indicated in Figs. 1 to 6 inclusive, the bulb 20 with its head 23 are preferably made of soft rubber, and the nozzle having the wall 34 and the 105 fingers 48 with their shanks 50 are preferably made of vulcanized hard rubber.

In Fig. 7, the bulb is again indicated at 20 with the pockets 30, and the head 23 having the port 24. The nozzle in this instance is indicated with the wall 64 similar to 34 having thickened portions and grooves

as described for the nozzle having the said wall 34. The wall 64 is integral with the bulb 20 and like the latter is made of soft rubber. In this modification the fingers are again indicated at 48 and the shanks are shown at 50.

Having described my invention what I desire to secure by Letters Patent and claim is:

10. 1. In a vaginal syringe the combination of a compressible bulb for a fluid, a pocket formed with the wall of the bulb, a nozzle having openings extending from the bulb and fingers having a shank formed therewith, said shank located in said pocket of the bulb, a compression of the bulb simultaneously swinging said fingers outwardly from the wall of the nozzle and discharging the fluid from the bulb through the openings 55 of the nozzle.
15. 2. In a vaginal syringe the combination of a compressible bulb for a fluid, a pair of pockets formed with the wall of the bulb, a nozzle extending from the bulb and having openings extending therethrough, said nozzle having seating grooves in its outer surface and two pairs of fingers each having a shank in fulcrumed relation to said bulb, each of said shanks seated in one of 60 the pockets of the bulb, said fingers normally seated in the seating grooves of the nozzle, said bulb when compressed at said shanks simultaneously discharging the fluid therefrom through the openings of the nozzle and expanding or swinging said fingers outwardly from said nozzle.
20. 3. In a vaginal syringe the combination of a compressible bulb for a fluid, a head at one end of the bulb, a pair of pockets formed

with the bulb, a hollow nozzle having openings with one end supported in and extending from the head of the bulb, said nozzle having seating grooves in its outer face and two pairs of fingers oppositely positioned and each having a shank, each of said shanks detachably seated in one of said pockets of the bulb, each pair of fingers normally seated in a pair of the seating grooves of the nozzle, each of said shanks at its upper end fulcrumed in the head of the compressible bulb, said bulb when compressed at said shanks simultaneously discharging the fluid therefrom through the openings in said nozzle and expanding or swinging said fingers outwardly from said nozzle.

4. In a vaginal syringe the combination of a compressible bulb, a head at the open end of the bulb, a hollow nozzle having openings at its outer end extending from the opening of said head, two pair of pockets formed with the wall of the bulb, the openings of said pockets extending through the head of the bulb and two pairs of fingers located to normally bear against the outer face of said nozzle, each pair of fingers having a shank formed therewith, said shanks located in said pockets and thereby hinged to the head of the bulb, a compression and release of said bulb between said shanks adapted to fill said bulb with a fluid and maintaining said fingers in contact with said nozzle, and a compression of said bulb over said shanks simultaneously discharging the fluid from the bulb and expanding or swinging said fingers from said nozzle.

In testimony whereof I affix my signature.

AARON DOLMATCH.
